UNITED STATES PATENT OFFICE.

EDWARD GURNEY, OF TORONTO, ONTARIO, CANADA, ASSIGNOR TO THE
GURNEY HOT WATER HEATER COMPANY, OF BOSTON, MASS.

DESIGN FOR A RADIATOR-SCREEN.

SPECIFICATION forming part of Design No. 17,240, dated April 5, 1887.

Application filed January 17, 1887. Serial No. 224,614. Term of patent 7 years. Patented in Canada April 2, 1886.

To all whom it may concern:

Be it known that I, EDWARD GURNEY, a citizen of the Dominion of Canada, residing at Toronto, in the Province of Ontario and Dominion of Canada, have invented and produced a new and original Design for Radiator-Screens, of which the following is a specification.

The nature of my design is fully shown in the accompanying print, forming a part of this specification.

The design consists of the following features, viz: first, the frieze or main portion *a*, composed of reticulated panel, the openings or reticulations being disposed to form the diaper-work or ornamentation shown; secondly, the base *b*, composed of the two horizontal reticulated bands or divisions, 2 3; thirdly, the cornice *c*, composed of the horizontal reticulated divisions 4 5, which are similar to the divisions

of the base, but arranged in inverse order; and, fourthly, the corner columns *d*, each composed of vertical reticulated divisions, 7 8, ornamented to harmonize with the ornamentation of the base and cornice, as shown. 25

I claim—

The design for a radiator-screen herein shown and described, the same consisting of the ornamental frieze or body, the base *b*, the cornice *c*, and the corners or columns *d*, the 30 said base, cornice, and columns being similarly ornamented, as shown.

In testimony whereof I have signed my name to this specification, in the presence of two subscribing witnesses, this 30th day of December, 1886. 35

EDWARD GURNEY.
